UNITED STATES PATENT OFFICE.

DANIEL KOPS, OF NEW YORK, N. Y.

APPAREL-CORSET.

1,260,210.

Specification of Letters Patent. Patented Mar. 19, 1918.

Application filed September 29, 1917. Serial No. 193,892.

To all whom it may concern:

Be it known that I, DANIEL Kops, a citizen of the United States, residing in the borough of Manhattan, city, county, and 5 State of New York, have invented an Improvement in Apparel-Corsets, of which the following is a specification.

My present invention relates to an apparel corset and more particularly to a front lace 10 and closed back corset garment. I am aware that heretofore apparel corsets of this type have been made in various manners, for example, a front lace corset as shown and described in Letters Patent No. 1,233,251 15 granted to me on July 10, 1917. In this garment however, together with the front lace devices which extend from the upper edge of the garment to a point appreciably above the lower ends of the front steels there are 20 also employed uplift tension straps associated with the lower portion of the front steels and adjustable to position to simultaneously exert an inward and an upward pressure against the abdomen of the wearer 25 to properly support the same. A garment of this type is advantageously employed in many instances. In other cases however, the uplift or support feature is not necessary or desirable but on the other hand in some 30 cases it is both necessary and desirable to produce a flattening or self-reducing effect on the abdomen of the wearer, and the corset made in accordance with the present invention is constructed to produce both the uplift and flattening effects, the former by the 35 lower portions of the lacing devices by which the garment is adjusted to position on the body, and the latter by the use of self-reducing straps, or the same in conjunction 40 with suitable tension straps.

In the present instance therefore, instead of employing the uplift tension straps I may include only the customary form of self-reducing straps in a front lace corset, 45 or in conjunction with these self-reducing straps in this form of corset I may also employ tension straps so placed in the garment as to effect a pull in the opposite direction from that produced by the self-reducing 50 straps and against the same portions of the abdomen of the wearer; that is to say, the pull exerted by the self-reducing straps is from the body of the garment toward the front steels, whereas the pull exerted by the 55 tension straps employed is from the front

steels toward the body of the garment, and the pulls exerted by these parts of the garment coact to exert a circumferential pressure against the same portion of the abdomen of the wearer to produce a flattening 60 effect of the same, or I may employ tension straps so constructed as to perform the functions of the ordinary self-reducing straps. In both these instances the lacing devices 65 preferably extend from the lower to the upper edges of the body proper of the corset garment; that is substantially from the lower ends of the front steels to the front edge of the body of the garment in order that the lower portions of the lacing devices 70 may be employed to effect an upward pressure against the body of the wearer when the garment is adjusted to position thereon. In all instances I also employ the tongue shown and described in Letters Patent No. 1,241,400 75 granted to me September 25, 1917, for use as a gage in determining the extent to which the lacing devices must be adjusted to make the parts of the garment symmetrical on the body of the wearer.

The corset made in accordance with my present invention will be hereinafter more particularly described in conjunction with the accompanying drawings in which:

Figure 1 is a perspective view illustrating 85 my improved apparel corset.

Fig. 2 is an enlarged elevation of the outer front portion of the garment.

Fig. 3 is an enlarged elevation of the inner front portion of the garment illustrating 90 a tongue employed to cover the lacing devices.

Fig. 4 is an enlarged elevation of the front portion of the garment embodying the tension straps employed in conjunction with the 95 self-reducing straps.

Fig. 5 is a view similar to Fig. 4 showing the use of the adjustable lacing devices in both sides of the garment.

Fig. 6 is an exterior elevation of the front 100 portion of the garment showing another form of the invention, and

Fig. 7 is an exterior elevation of the front portion of the garment showing a still further modification of the invention.

Referring to the drawing and more particularly to Figs. 1, 2 and 3, the corset made in accordance with this invention comprises a body member 10 which is preferably closed at the back and provided with lacing devices 110

in the front for adjustably securing the garment in position on the body of the wearer. As is customary the garment is divided at the front thereof and fitted with front steels 11 and 12. Connected to these are the usual clasp members 13 by which the front steels of the garment are connected to one another when in use. The front steel 11 is permanently secured in the left hand side of the 10 garment as illustrated in the drawings and the front steel 12 is similarly connected in a front steel section 14. Adjacent the edge of the front steel section 14 there is a series of eyelets 15 and in similar positions in the adjacent edge of the body of the garment there 15 is a series of eyelets 16. Laces 17 are threaded through the eyelets 15 and 16 so as to complete the lacing devices by which the garment is adjusted to position on the body, 20 and these lacing devices as illustrated in the drawing, preferably extend from the upper edge of the garment to a point slightly above the lower ends of the front steels, that is from the upper edge to the lower edge of 25 the body member proper, or the lower edge of the abdominal section of the garment, so that by the adjustment to position in this as well as in other forms of the invention, the lower portions of these lacing devices 30 adjust the lower front steel sections of the garment to position to effect an upward pressure against the abdomen of the wearer.

As illustrated in the drawing and as particularly shown in Fig. 3, I include in this 35 garment a tongue member 18 associated with the adjustable side for the lacing devices. Along one edge this tongue is connected to the body of the garment by a line of stitching 19 or otherwise and along its 40 opposite edge the tongue is connected to the front steel section 14 by a line of stitching 20 or otherwise. As described in the Letters Patent aforesaid, this tongue is fitted with stays 21 running longitudinally thereof and relatively short stays 22 extending transversely between the stays 21. These 45 stays are employed to enable the user to determine the extent to which the lacing devices must be adjusted to make the parts of the garment symmetrical on the body, 50 this being determined when the longitudinal stays 21 lie substantially immediately behind the series of eyelets 15 and 16.

In order to produce a flattening effect I 55 employ self-reducing straps 23 and 24. The self-reducing strap 23 as illustrated is in the left hand side of the garment and along one edge is connected by a line of stitching 25 to the body of the garment and also to 60 the skirt 26 depending from this side of the body member of the garment. At its upper, lower, and forward edges, this self-reducing strap is free from the garment. In its forward edge and adjacent the top 65 thereof this self-reducing strap 23 is pro-

vided with eyelets 27 adapted to engage with a hook 28 fixed in the lower end of the front steel 11 so as to enable the wearer to adjust the self-reducing strap to the proper position. On the other side of the garment 70 the self-reducing strap 24 is secured along one edge by a line of stitching 29 to the body of the garment and also to the skirt 30 depending therefrom. This self-reducing strap at its upper, lower, and forward 75 edges is also otherwise free from the garment. Similar to the self-reducing strap 23 it is also provided with eyelets 31 any one of which is adapted to engage with a hook 32 secured in the lower end of the 80 front steel 12 for adjusting this self-reducing strap to position. This self-reducing strap 24 as indicated in Fig. 2 may be provided with a strap 33 suitably secured to the inner side thereof and extending in the 85 direction of the pull exerted by the self-reducing strap. The strap 33 extends beyond the forward edge of the self-reducing strap and is provided with eyelets 34 90 preferably in alignment with the eyelets 31 95 so as to provide for an additional extension and adjustment of the self-reducing strap to position depending of course upon the position to which the lacing devices are adjusted. 95

In this garment I also employ hose supporter extensions 35 and 36 depending from the front steel sections of the garment. The hose supporter extension 35 is preferably gore-shaped and at its upper and for a portion of its side edges is suitably secured to the body of the garment as clearly indicated in Fig. 2. The hose supporter extension 36 however is unconnected to the body of the garment and is secured entirely to the front 100 steel section 14. In its upper end the hose supporter extension 36 preferably overlaps a portion of the body of the garment and at its inner extremity 37 is provided with an eyelet 38 through which the lace 17 also 110 passes in order to assist in maintaining this hose supporter extension in position. The hose supporter extensions 35 and 36 may be provided with hose supporters 39, and the lower edges of the self-reducing straps 23 115 and 24 with hose supporters 40 and 41 respectively as indicated in Fig. 2 of the drawing. 115

In the use of this garment as will be 120 readily appreciated the self-reducing straps exert a circumferential pressure against the abdomen of the wearer and the pull of each strap as shown in Fig. 2 to effect this pressure is from the body of the garment to which it is attached permanently toward the 125 front steel to which it is adjustably attached.

By referring to Fig. 4 it will be seen that in addition to the tension exerted by the self-reducing straps I may provide for an additional tension exerted on and against 130

the same portion of the abdomen, and also in the same direction. This is effected by employing the upper ends of the hose supporter extensions together with additional 5 devices as auxiliary tension straps. In Fig. 4 the upper end of the hose supporter extension 36 is indicated at 42 and at its extremity is fitted with a series of eyelets 43. Adjustably secured to the body of the garment 10 is an anchor strap 44. This is preferably secured in the body of the garment along the same line of stitching which connects the self-reducing strap thereto, and in this anchor strap there is a series of eyelets 44 15 corresponding to the eyelets 43. A lace 46 is threaded through the eyelets 43 and 45 and also passed through eyelets 47 in the corresponding skirt member of the garment so that this lace may be adjusted exteriorly 20 of the garment to obtain the desired position of this auxiliary tension strap. Similarly on the other side of the garment the upper end 48 of the hose supporter extension 35 is fitted with a series of eyelets 49. Adjacent 25 this end of the hose supporter extension is an anchor strap 50 corresponding to the anchor strap 44, and in the anchor strap 50 there is a series of eyelets 51. Threaded through the eyelets 49 and 51 is 30 a lace 52 which is also threaded through eyelets 53 in the skirt of the garment so that the lace may be drawn up to adjust the auxiliary tension strap in this side of the garment in a position similar to that here- 35 inbefore described in the other side of the garment.

Referring to Fig. 5 the construction is in every way similar to that shown in Fig. 4 with exception that the front lacing devices 40 for adjusting the garment to position are employed in the left hand side of the corset as well as in the right hand side thereof. These similar lacing devices include the front steel section 54 in which the front steel 45 11 is secured, a series of eyelets 55 placed along the edge of the front steel section 54, a series of eyelets 56 along the edge of the adjacent portion of the body of the garment, and a lace 57 threaded through the eyelets 50 55 and 56 together with a tongue member 58 which is similar in all respects to the tongue member 18.

It will be apparent that in the use of the garment constructed as shown in Figs. 4 55 and 5, the pull of the self-reducing straps is from the body of the garment toward the front steels, whereas the pull of the auxiliary tension straps is from the front steels toward the body of the garment, and these parts as 60 hereinbefore stated, coact to exert a pressure in the same direction and over the same portion of the abdomen of the wearer, this pressure being exerted in a substantially circumferential line so as to produce a flattening effect.

By reference to Fig. 6 it will be seen that I may dispense with the ordinary form of self-reducing strap and employ tension straps placed exteriorly of the garment to perform the functions of these ordinary 70 self-reducing straps. In this structure the skirt at the lower front portion of the garment is continuous and connected to the extensions of the members inclosing the front steels. On the right side of the garment 75 immediately below the lacing devices which are the same as those hereinbefore described in connection with the other forms of the invention I employ a tension strap 59, and in a similar position on the left side of 80 the garment a tension strap 60. Associated with the tension strap 59 is an anchor strap 61 suitably connected along one edge to the body of the garment forward of the hip section, and similarly associated with the 85 tension strap 60 is an anchor strap 62, secured to the body of the garment on the left side thereof in a position corresponding to that in which the anchor strap 61 is connected in the right hand side. Along the 90 inner edge of the tension strap 59 there is a series of eyelets 63 and in the adjacent edge of the anchor strap 61 a corresponding series of eyelets 64. A lace 65 is threaded through eyelets 63 and 64 and passed through a slot 95 66 provided therefor in the skirt of the garment, and also threaded through eyelets 67 so that the lace may be adjustable exteriorly thereof. In the same manner on the other side of the garment the tension strap 60 at 100 its inner edge is provided with a series of eyelets 68, the adjacent edge of the anchor strap 62 with a corresponding series of eyelets 69. A lace 70 is threaded through the eyelets 68 and 69, passed through a slot 71 105 in the skirt of the garment and also threaded through eyelets 72 so that the lace 70 may be drawn up to adjust the position of the tension strap exteriorly of the garment. In this form of the invention the tension straps 110 are adjusted to place to exert a circumferential pressure against the abdomen of the wearer of the garment to effect the flattened result that is obtained in the use of the other forms of the invention. 115

Referring to Fig. 7 it will be seen that in a garment having front lacing devices similar to those hereinbefore described I may also employ a form of tension strap which is doubly adjustable to effect the same results as in the other forms of the invention. In this form of garment the skirt at the lower front section is also continuous and preferably includes a portion of the tongue member as shown in Fig. 3 but which in this 120 instance is overlapped to form a fold in the lower front portion of the garment on the side in which the lacing devices are employed. In this or the right hand side of the garment I employ a tension strap 73 125 130

which is suitably secured along the forward edge in the section on the extension thereof on which the corresponding front steel is secured. At its inner or opposite edge this tension strap is fitted with a series of eyelets 74. Associated with this tension strap is a strap 75 fitted with a series of eyelets 76 corresponding in number and position with the eyelets 74. Also forming part of this tension device are straps 77 and 78 which at corresponding ends are suitably secured in the strap 75 and respectively are threaded through loops 79 and 80 suitably secured in the body of the garment forward 15 of the hip section and brought together at their opposite edges so as to be connected to the lower front steel section of the garment as hereinafter described.

A lace 81 is threaded through the eyelets 20 74 and 76 also through a slot 82 provided therefor in the skirt of the corset and through eyelets 83 so that the lace may be drawn up to adjust the position of the parts of the tension strap exteriorly of the corset.

25 At their free ends where they are joined together the straps 77 and 78 are fitted with a row of eyelets 84 any one of which is adapted to engage with a hook 85 and fixed in the lower end of the corresponding corset steel. Similarly on the other side of the garment I employ a tension strap 86. At its free end this is provided with a series of eyelets 87. Associated with the tension strap 86 is a strap 88 in which there is a series of eyelets 89 corresponding in number and position to the eyelets 87 in the tension strap 86. The strap 88 is secured to the corresponding ends of straps or tapes 90 and 91 which respectively are passed through loops 92 and 93 made of metal or other similar material and suitably secured to the body of the garment forward of the hip section in a position similar to that in which the loops 79 and 80 are secured in the opposite side of the corset. A lace 94 is threaded through eyelets 87 and 89, also through a slot 95 provided therefor in the skirt of the corset, and through eyelets 96 so that this lace may be drawn up exteriorly of the garment to adjust the parts of the tension strap to position. The other or free ends of the straps 90 and 91 are secured to one another and fitted with eyelets 97 either one of which is adapted to engage with a hook 98 secured for this purpose on the lower end of the corresponding corset steel. In this form of the invention it will be apparent that the tension strap member performing the functions of the ordinary self-reducing strap is doubly adjustable by the straps 77 and 78 on the one side, 90 and 91 on the other side, being made so as to engage in any one of a number of positions at their free ends with the hooks provided for this

50 purpose in the lower front portions of the 55 corset steels and also after this adjustment is effected by the adjustment of these parts by means of laces 81 and 94.

55 In my co-pending application Serial No. 194,450 I have shown and described a corset structure which is analogous to that disclosed in the present case. In the aforesaid co-pending application however, while the lacing devices and the functions performed by the same are in every respect similar to the same parts of the garment in the present case, the hose supporter straps and hose supporters therein shown and described in connection with that portion of the corset to which the invention relates are entirely independent of the skirt sections of the garment and coact with the self-reducing straps for producing a circumferential pressure against the body of the wearer, whereas in the present case the hose supporters associated with that portion of the corset to which this invention relates are directly connected to the self reducing straps.

60 I claim as my invention:

65 1. An apparel corset comprising a body member, front steels adapted to be connected to one another, lacing devices for connecting one front steel to the adjacent portion of the body member and extending upwardly from the lower edge of the abdominal section of the garment whereby in the adjustment thereof the lower portion of the lacing devices acts to produce an upward pressure, self-reducing straps extending below the lower ends of the lacing devices and adjustable to position in the garment, and tension straps underlying the self-reducing straps and also adjustable to position in the garment, the said self-reducing straps and tension straps coacting to exert a circumferential pressure against the body of the wearer.

70 2. In apparel corset comprising a body member, front steels adapted to be connected to one another, lacing devices for connecting one front steel to the adjacent portion of the body member and extending upwardly from the lower edge of the abdominal section of the garment whereby in the adjustment thereof the lower portion of the lacing devices acts to produce an upward pressure, and self-reducing straps each extending below the lower end of the lacing devices and secured at one end to a part of the garment and adjustably connected at the other end to another part of the garment for exerting a circumferential pressure against the body of the wearer.

75 3. An apparel corset comprising a body member, front steels adapted to be connected to one another, lacing devices for connecting one front steel to the adjacent portion of the body member and extending upwardly from the lower edge of the abdominal section of the garment whereby in the

adjustment thereof the lower portion of the lacing devices acts to produce an upward pressure, self-reducing straps each extending below the lower end of the lacing devices and secured at one side to a part of the garment and adjustably connected at the other side to another part of the garment, and tension straps underlying the said self-reducing straps and also connected at one side to a part of the garment and adjustably connected at the other side to another part of the garment, the said self-reducing and tension straps coacting to exert a circumferential pressure against the body of the wearer.

4. An apparel corset comprising a body member, front steels adapted to be connected to one another, lacing devices for connecting one front steel to the adjacent portion of the body member and extending upwardly from the lower edge of the abdominal section of

the garment whereby in the adjustment thereof the lower portion of the lacing devices acts to produce an upward pressure, self-reducing straps each connected along one edge adjacent the hip section of the garment and adjustably connected at its opposite edge at the lower front steel section of the garment, tension straps each connected at one side on the lower front steel section of the garment and adjustably connected at its opposite side adjacent the hip section of the garment and underlying the self-reducing strap on the corresponding side of the garment, the said self-reducing straps and tension straps coacting to exert a circumferential pressure against the body of the wearer.

Signed by me this 27th day of September, 1917.

DANIEL KOPS.
